UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed September 20, 1921. Serial No. 501,998.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to sound-deadening devices for typewriting machines.

To deaden or muffle the sound of the machine, it has been proposed to enclose it by a sound-deadening cabinet or casing, allowing only the keyboard section of the machine 15 and various finger-pieces on the carriage to extend from the cabinet so that the machine may be operated.

A feature of the present invention is to have the frame of the machine form part 20 of the casing, thus avoiding the necessity of a separate casing or cabinet.

To this end the usual openings in the frame, through which access may be had to the interior mechanism, are sealed with 25 closures, and the upper part of the machine is provided with a dome extending over the frame beyond its sides to form a chamber in which the carriage operates.

The front wall of the main frame is provided with a releasable plate to close the usual opening therein, said plate having lateral extensions and being effective to 30 close the carriage chamber at the front.

A work-sheet chamber is provided at the rear of the machine into which hang the ends of work-sheets from the carriage, said chamber extending downwardly from the carriage chamber and forming a closure for the rear opening in the frame.

40 This arrangement is not only pleasing in appearance and occupies less space on a support, but since the parts forming the carriage chamber and the work-sheet chamber are integral with the frame they are more rigid. Further the machine may readily be transported with its chambers as a single unit.

Other features and advantages will hereinafter appear.

50 In the accompanying drawings,

Figure 1 is a side view, vertically sectioned, of an Underwood Standard typewriting machine with the sound-deadening devices applied thereto.

Figure 2 is a side elevation of the device 55 shown in Figure 1.

Figure 3 is a disassembled perspective view of the sound-deadening devices.

Figure 4 is a perspective view of the device shown in Figure 1. 60

Figure 5 is a front elevation, partly sectioned, of the device shown in Figure 1.

Figure 6 is a plan view of the device shown in Figure 1, with certain of the sound-deadening devices removed. 65

The Underwood Standard typewriting machine comprises a main frame 10 and a forward extension 11, in which are positioned banks of keys 12 at the ends of key-levers 13 operating in a guide-plate or comb-plate 15, said key-levers operating type-bars 14 to cause types 16 carried thereby to print against a platen 17 mounted in a platen-frame 18. Said frame forms part of a carriage 20 mounted for letter-feeding movement upon a front rail 21 and a rear rail 22 on the main frame. The carriage is provided with various forwardly-extending handles, such as a line-space handle 25. 70

The machine, as described above, has 80 openings at the bottom, sides, back, top and front, through which sounds produced in the typing operation may be transmitted to the outside, and sound-deadening means is provided for closing each of said openings. For closing the bottom opening, there is provided a closure member 30, which may be in the form of a pan-shaped plate having at its upper edges outwardly-extending flanges 31, to bear against the lower edges 85 of the typewriter frame. The plate may be supported upon feet 32 similar to the usual typewriter supporting feet, and may be fixed to the main frame preferably by screws 33, which extend upwardly through the feet and into the usual corner posts 35 of the typewriter frame. The typewriting machine is thus fixed in position relatively to the plate, and both the machine and the plate are supported upon said feet 32. 90

At the front of the machine, there is an opening between the guide-plate 15 and the base and an opening above the key-levers in which the type-bars are disposed. For closing the opening beneath the comb-plate, the plate 30 may be provided at the front with an upward extension 38, which extends from the plate 30 to the guide-plate to which it 100

may be attached, slots 40 being provided for the passage of the usual arms or levers supporting the space-bar. The opening above the key-levers is closed by a front plate 41 supported upon the machine in any suitable manner, as by screws 42 threaded into the frame 10, and having openings through which the line-lock release key 43 and the shaft supporting the ribbon-color shift-key 10 44 extend.

The usual openings at the sides of the machine, through which access may be had to the interior mechanism, may be closed by closures 50 in the form of detachable plates 15 mounted on the typewriter frame in any suitable manner, herein shown as by screws. To close the opening at the top of the machine, it is necessary to provide a closure which may form chambers in which the 20 typewriter-carriage and the work-sheets which it carries may operate freely. For this purpose, there are provided horizontal extensions 52 fixed preferably to flanges 53 on the upper edges of side plates 50 and 25 having front flanges 54 fixed to the front plate 41, said front plate and extensions thus mutually supporting each other. A container or chamber 60, which may be closed except at the top, is provided at the 30 rear of the machine, the overhanging ends of work-sheets carried by the typewriter-carriage operating in said container. Said container extends between the extreme side edges of the horizontal extensions 52, and 35 is supported upon side flanges 62 and depending flanges 63 on said extensions and upon the rear flange 31 of the bottom plate 30. The container 60 thus forms vertical extensions at the rear and side edges of the typewriter, and serves as a closure for the 40 rear opening in the typewriter frame. To close the openings at the top, there is provided a cover 70 which extends from one side flange 62 of the horizontal extension 52 45 to the other and from the front plate 41 to the rear wall 66 of the container 60. The cover thus completely covers the opening at the top, regardless of the position of the typewriter-carriage and its work-sheets. 50 Preferably, the cover is hinged to the upper edge of rear wall 66 of the chamber 60, and is swung upwardly when access to the machine is desired, the upward movement being facilitated by a spring 71 fixed at one 55 end to an arm 72 carried by the cover and at the other end to a lug 73 upon the horizontal extensions 52 secured to the machine frame, and normally tending to open the cover, the weight of the cover being sufficient to hold it closed. The cover may be 60 provided with a window 74 to permit the typewriter carriage and the work-sheets positioned therein to be viewed.

The cover has a front wall 80, which terminates some distance above the top of

front plate 41 to form a slot through which the various carriage-operating handles, such as line-space handle 25, extend. The slot is closed preferably by co-operating cushions 81 and 82 fixed upon the front 70 wall 80 and front plate 41, respectively.

To thoroughly close the dome when the cover is down, the side walls of the cover overlap and engage the outer faces of the side flanges 62 on the lateral extensions 52, 75 Figure 5. To arrest the cover in its closed position, it is provided with shoulders 85 (Figures 3 and 4), which engage the upper edge of the front plate 41.

It is apparent from the above description 80 that all of the openings from the interior of the machine to the outside are closed by the various closure elements, and that said elements are carried by the machine. All of the various closures may be provided 85 with linings 86 of sound-deadening material.

The sound is substantially confined in a space which is substantially walled in with sound-absorbing material forming the plate 90 linings, so that the sound may be reflected from wall to wall and gradually become absorbed.

Variations may be resorted to within the scope of the invention, and portions of the 95 improvements may be used without others.

Having thus described my invention, I claim:

1. Sound-deadening means for a typewriting machine having a frame and feet at 100 the four corners thereof, said sound-deadening means comprising a plate inserted between said feet and said frame and extending to the rear of the frame to form a shelf, and a closure for the back of the frame resting 105 on said shelf.

2. Sound-deadening means for a typewriting machine having a frame and feet at the four corners thereof, said sound-deadening means comprising a plate inserted between 110 said feet and said frame and extending to the rear of the frame to form a shelf, and a closure for the back of the frame resting on said shelf, said closure for the back of the frame comprising a pocket 115 to receive the end of a work-sheet extending downwardly over the back of the machine and to permit movement of the work-sheet laterally of the machine.

3. Sound-deadening means for a typewriting machine having a frame, key-levers in the lower part of the frame and projecting from the front thereof, a key-lever comb-plate at the front of the frame, and feet at the four corners of the frame, said sound-deadening means comprising a plate inserted between the feet and bottom of the frame to close the bottom of the frame, and having an upwardly-extending flange at its forward edge to cooperate with said comb- 120

plate to prevent the escape of sound beneath the key-levers.

4. Sound-deadening means for a type-writing machine having a frame with side openings and a carriage to travel on said frame, said sound-deadening means comprising closures for said side openings fastened to the outside of said frame, lateral extensions to accommodate the travel of said carriage and secured to said side closures, a pocket secured to said lateral extensions at the rear and extending downwardly over the rear of the frame to close the back thereof, said pocket also serving to accommodate a work-sheet extending downwardly from the carriage and traveling therewith laterally of the machine, and a cover hinged to the back of the pocket and closing said lateral extensions when in lowered position.
5. Sound-deadening means for a type-writing machine having a frame with side openings and a carriage to travel on said frame, said sound-deadening means comprising closures for said side openings fastened to the outside of said frame, lateral extensions to accommodate the travel of said carriage and secured to said side closures, a pocket secured to said lateral extensions at the rear and extending downwardly over the rear of the frame to close the back thereof, said pocket also serving to accommodate a work-sheet extending downwardly from the carriage and traveling therewith laterally of the machine, a cover hinged to the back of the pocket and closing said lateral extensions when in lowered position, and a closure for the bottom of said frame spaced above the support on which the typewriter rests and secured to said pocket at its rear.
6. Sound-deadening means for a typewriter having a frame and a traveling carriage thereon, said sound-deadening means comprising side closures attached to the frame on the outside thereof, a body having lateral carriage-travel-accommodating extensions to rest on the side closures, and a pocket to accommodate a work-sheet extending downwardly at the rear of the carriage and to serve as a closure for the rear of said frame, said pocket being attached to said lateral extensions at the rear thereof, and a cover to close the top of said pocket and said lateral extensions.
7. Sound-deadening means for a typewriter with a frame having openings in the sides and back and a traveling carriage on said frame, said sound-deadening means comprising a back closure in the form of a pocket open at the top to receive the end of a work-sheet hanging down from the carriage at the rear, the front wall of the pocket engaging the back of the frame and the pocket being of substantially the same length as the travel of the carriage.
8. Sound-deadening means for a type-

writer with a frame having openings in the sides and back and a traveling carriage on said frame, said sound-deadening means being supported by said frame and comprising a back closure in the form of a pocket open at the top to receive the end of a work-sheet hanging down from the carriage at the rear, the front wall of the pocket engaging the back of the frame and the pocket being of substantially the same length as the travel of the carriage.

9. Sound-deadening means for a type-writing machine, comprising plates closing the bottom, sides and front thereof, and a working chamber for the carriage and depending work-sheets closing the top and rear of the machine, and supported by the end plates and machine-frame.

10. Sound-deadening means for a type-writing machine having key-levers and a frame from which said key-levers project and having a front opening above the key-levers, said sound-deadening means comprising side extensions mounted on said frame to accommodate the travel of the carriage, a cover to close said side extensions at the top, and a plate secured to the front edges of said extensions to close said opening in the frame.

11. Sound-deadening means for a type-writing machine, said machine having key-levers, said machine having an opening above said key-levers, an opening below said key-levers, and an opening at the bottom, said sound-deadening means comprising a plate mounted on said machine for closing said bottom opening, and an upward extension on said plate for closing said opening below the key-levers, and a plate carried by said machine for closing said opening above said key-levers.

12. Sound-deadening means for a type-writing machine, said machine having a carriage and an opening at the top, said sound-deadening means comprising a closure for said opening, said closure comprising extensions mounted on said machine and over which said carriage operates, and a cover extending over said machine and said extensions.

13. Sound-deadening means for a type-writing machine, said machine having openings at the top and sides, said sound-deadening means comprising a closure mounted on the machine for closing each side opening, and a closure for said top opening, said last-named closure being mounted on said side closures, and forming therewith a working chamber for the carriage.

14. Sound-deadening means for a type-writing machine, said machine having a carriage and openings at the top and sides, said sound-deadening means comprising plates mounted on the machine for closing said side openings, extensions mounted on

said plates and over which said carriage operates, and a cover enclosing said extensions and the top of said machine.

15. Sound-deadening means for a type-writing machine, said machine having a carriage and openings at the top and sides, said sound-deadening means comprising a closure mounted on the machine for closing each side opening, a pocket mounted on said machine and in which operate work-sheets carried by said carriage, said pocket being open at the top, and a closure mounted on said pocket for closing the top of said machine and said pocket.

15 16 Sound-deadening means for a type-writing machine, comprising plates closing the bottom, sides and front thereof, and a working chamber for the carriage and depending work-sheets closing the top and 20 rear of the machine, and supported by the end plates and machine-frame, the chamber having a portion at the rear depending to the bottom of the machine and closing the rear thereof, in which the depending work-sheets travel.

17. Sound-deadening means for a type-writing machine, said machine having a carriage and openings at the top and sides, said sound-deadening means comprising a closure mounted on the machine for closing each side opening, extensions mounted on the side closures, a pocket mounted on said extensions and in which operate work-sheets carried by said carriage, said pocket being open at the top, and a closure mounted on said pocket and extending over said extensions for closing said top opening and the top of said pocket.

40 18. Sound-deadening means for a type-writing machine, said machine having a carriage and openings at the top, rear and sides, said sound-deadening means comprising plates mounted on the machine for closing said side openings, extensions mounted 45 on said plates and over which said carriage operates, a pocket mounted on said extensions and in which operate the overhanging ends of work-sheets carried by said carriage, said pocket being open at the top and closing said rear opening, and a cover mounted 50 on said pocket and extending over said extensions for closing said top opening and the top of said pocket.

55 19. Sound-deadening means for a type-writing machine, said machine having a carriage and openings at the top and bottom, said sound-deadening means comprising a closure for said bottom opening, a pocket open at the top mounted on said closure and in which operate the overhanging ends of work-sheets carried by the carriage, and means for closing the opening at the top of the machine and the top of said pocket.

60 20. Sound-deadening means for a type-writing machine, said machine having a car-

riage and openings at the top and bottom, said sound-deadening means comprising a closure for said bottom opening, a pocket open at the top mounted on said closure and in which operate the overhanging ends of work-sheets carried by the carriage, said pocket being closed at the bottom and forming a continuation of said bottom closure, and means for closing the opening at the top of the machine and the top of said pocket.

70 21. Sound-deadening means for a type-writing machine, said machine having a carriage and openings at the top and bottom, said sound-deadening means comprising a plate for closing said bottom opening, a pocket open at the top mounted on said plate and in which operate the overhanging ends of work-sheets carried by the carriage, said pocket being closed at the bottom, the plate extended to lap upon the bottom of the pocket and secured thereto, and means for closing the opening at the top of the machine and the top of said pocket.

75 22. Sound-deadening means for a type-writing machine, said machine having key-levers, a carriage, and various operating levers extending forwardly from said carriage, said machine having a top opening and a front opening above said key-levers, said sound-deadening means comprising means secured to said machine for closing said front opening, means secured to said machine for closing said top opening, said first-named means and said second-named means forming a slot at the front through which said carriage-operating levers extend.

80 23. Sound-deadening means for a type-writing machine, comprising a working chamber for the carriage and work-sheets depending therefrom, and closures secured to the bottom, sides and front of the type-writing machine, the carriage working chamber secured to said bottom and side closures.

85 24. Sound-deadening means for a type-writing machine, comprising a working chamber for the carriage and work-sheets depending therefrom, and closures secured to the bottom, sides and front of the type-writing machine, the carriage working chamber secured to the bottom and side closures, and co-operating with the front closure to form a slot for the operating handles of the machine.

90 25. Sound-deadening means for a type-writing machine, said machine having key-levers, a carriage, various operating levers extending forwardly from said carriage, said machine having openings at the bottom, sides, top, and at the front above and below said key-levers, said sound-deadening means comprising a plate mounted on said machine for closing said bottom opening, said plate having an upward extension for closing the

opening beneath the key-levers, a front plate mounted on said machine for closing the opening above the key-levers, side plates mounted on said machine for closing said side openings, extensions mounted on said side plates and on said front plate and over which said carriage operates, a pocket supported upon the bottom plate and attached to said extensions and in which operate the overhanging ends of work-sheets carried by said carriage, said pocket being closed at the bottom to form a continuation of the bottom plate and being open at the top, and a cover mounted on said pocket and extending over said extensions for closing the top openings of the machine and the pocket, said cover forming with said front plate a slot at the front through which said carriage-operating levers extend.

26. The combination with a typewriting machine comprising a main frame closed at the bottom and sides and a carriage traveling on said frame, of a paper-pocket to receive a work-sheet hanging down from the rear of the carriage and having a front wall to engage the back of the frame and act as a closure therefor, and a dome to accommodate the travel of the carriage and to co-operate with said frame and paper-pocket to enclose the upper part of the machine.

27. The combination with a typewriting machine comprising key-levers, a main frame closed at the bottom, sides and back and having an opening at the front above the key-levers and a carriage to travel on said frame, of a sound-deadening dome to close the top of the machine and accommodate the travel of the carriage, said dome comprising side extensions beneath the path of the carriage and secured to the sides of the frame, a front plate attached to the front edges of said extensions and closing the front opening in the frame, and a cover to close the tops of the extensions, the side walls of the cover passing outside of the ends of said extensions and the cover being provided with portions to engage the front plate and limit the downward movement of the cover.

28. A typewriting machine comprising a frame closed at the back, sides and bottom, a paper carriage at the top of said frame, and means to close the top of said frame to form a chamber to enclose the carriage and accommodate the travel thereof, said chamber being supported by the frame of the machine.

29. A typewriting machine comprising a frame closed at the sides and bottom, a paper carriage at the top of said frame, closing means for the top of said frame having lateral extensions on the frame to form a chamber in which the carriage operates, and closing means for the back of the frame forming a chamber extending downwardly

from said first-named means at the back of the machine to receive the overhanging end of a work-sheet on the carriage.

30. In combination, a typewriting machine having a framework, a sound-deadening hood above the framework and providing a working chamber for the carriage and forming an air-pocket confining the sound rising from the machine, and means securing said hood upon said framework, 70 said hood including a cover-part liftable from over the carriage while the hood remains secured to the framework, 75 said hood including a cover-part liftable from over the carriage while the hood remains secured to the framework.

31. In combination, a typewriting machine having a framework, a sound-deadening hood above the framework and providing a working chamber for the carriage and forming an air-pocket confining the sound rising from the machine, and means securing said hood upon said framework, 80 said hood including a cover-part liftable from over the carriage while the hood remains secured to the framework, said chamber having a depending portion closing the rear of the machine-frame and secured to said frame and providing a pocket for the travel of depending work-sheets.

32. In combination, a typewriting machine having a framework, a sound-deadening hood above the framework and providing a working chamber for the carriage and forming an air-pocket confining the sound rising from the machine, means securing said hood upon said framework, said hood including a cover-part liftable from over the carriage while the hood remains secured to the framework, said chamber having a depending portion closing the rear of the machine-frame and secured to said frame and providing a pocket for the travel of depending work-sheets, and closures secured to the bottom, sides and front of the machine-frame.

33. In combination, a typewriting machine having a framework, a sound-deadening hood above the framework and providing a working chamber for the carriage and forming an air-pocket confining the sound rising from the machine, and means securing said hood upon said framework, 110 said hood including a cover-part liftable from over the carriage while the hood remains secured to the framework, said hood closing the top and rear of the machine-frame and secured to the rear thereof.

34. The combination of a typewriting machine having a framework provided with feet, a sound-subduing casing secured to said framework, said casing including a flooring beneath said framework, said flooring being secured at the other side of said framework by means of said feet extending beyond the framework, said casing also including a body-portion set down upon the flooring, and means securing said body-portion 125 130

tion to said flooring, the casing also including a top for said body-portion.

35. The combination with a typewriting machine having a framework provided with feet, of a sound-subduing casing secured to said framework, said casing including a flooring beneath said framework, said flooring being secured to the under side of said

framework by means of said feet and extending beyond the framework, said casing also including a body-portion set down upon said flooring, an overlapping flange joint being provided forming an interfit between the flooring and the bottom of the casing-body. 10

JOHN WALDHEIM.
